IMPACT CLUTCH

Frithiof P. Forss, Aurora, Ill., assignor to Independent Pneumatic Tool Company, Chicago, Ill., a corporation of Delaware

Application April 23, 1943, Serial No. 484,157

16 Claims.

(Cl. 192—30.5)

1

This invention relates to portable power operated impact wrenches for screwing up and unscrewing nut and bolts by power.

The invention, while relating to tools of the character referred to, is particularly concerned with the impact clutch mechanism employed in such tools for delivering a series or succession of rapid and relatively powerful rotational hammer blows on the anvil member of the clutch to tighten the nut or bolt after it has been set or to loosen a tight nut or bolt on removing the same, the invention having among its principal objects the following:

To provide an impact clutch of the roller type, that is, wherein the impact elements are in the form of solid, relatively long, heavy metal rollers freely mounted in recesses in the hammer member of the clutch for movement into and out of clutching engagement with the jaw or abutments on the anvil member for imparting rotation thereto in the operation of the clutch;

To locate the roller elements wholly within the recesses and in sliding contact with the end walls thereof and provided with tapered opposite ends to prevent the extremities of the rollers striking the abutments on tilting of the roller elements in the recesses; and

To provide a flexible driving connection between the rotary driver for the clutch and the hammer member of a character whereby the impact of the roller elements on the hammer member on releasing the abutments will rotate the hammer member ahead of the driver to absorb such impacts by overcoming the inertia of the hammer member to prevent premature wear on the hammer member and the recoil of the roller elements against the anvil member.

The invention consists further in the features hereinafter described and claimed.

In the accompanying drawings—

Fig. 1 is a side elevational view with parts broken away and in longitudinal section of an impact wrench embodying a clutch construction of my invention;

Fig. 2 is a cross-sectional view taken on line 2—2 of Fig. 1 showing the roller elements in their clutching positions;

Fig. 3 is a similar sectional view taken on line 3—3 of Fig. 1 to illustrate the flexible drive between the tool motor and the hammer member of the clutch; and

Fig. 4 is a sectional view similar to that of Fig. 2 showing the roller elements in the track-ways approaching the anvil abutments.

In the accompanying drawings, I have shown a

portable, pneumatically operated impact wrench of the type in which the motor section 1 of the tool occupying the upper half portion of the machine is bolted or otherwise rigidly secured in axial alignment to the clutch containing section 2 which occupies the lower half portion of the tool. The motor section 1 has a side or other handle 3 through which compressed air is supplied to the tool for operating the tool motor. The handle 3 has a fitting 4 at its outer end for connection with an air supply hose (not shown) as in tools of this character. The handle 3 mounts a throttle valve, also not shown, which by a trigger 5 in the handle enables the operator handling the tool to control the supply of motive fluid thereto.

In the tool shown, the motor is of the rotary type having a blade-provided rotor 6, the lower shaft section 7 of which extends into the upper end of the clutch section 2 for driving the hammer member 8 of the clutch through a flexible drive to be later described.

The outside casing 9 of the clutch section 2 houses and mounts the operative mechanism of the clutch and provides a journal for the spindle 10 at the lower end of the hollow cylindric anvil member 11 of the clutch. The anvil member 11 receives the hammer member 8 in concentric relation within its outer surrounding annular wall 12 and which wall member is provided with a pair of diametrically disposed, inwardly extending, radial abutments or shoulders 13, 13. These abutments 13 are integral with the anvil wall 12 and extend axially thereof as indicated in dotted lines in Fig. 1. The wall member 12 between the abutments 13 is formed with arcuate track-ways 14, 14 for the impact roller elements 15, 15 of the clutch to be presently described. The trackways 14 are made on a radius slightly greater than that of the hammer member 8 to provide clearance spaces therebetween for centrifugal force to move the roller elements 15 into the trackways to engage the abutments 13 as shown in Figs. 2 and 4. This positions the roller elements 15 for clutching the anvil and the hammer members for rotation in unison when running a free nut or bolt and for delivering a series or succession of rotational hammer blows on the abutments when the anvil member is held against rotation by the nut or bolt.

The roller elements 15 engage and/or strike against the opposite side edges 16, 16a of the abutments 13 said side edges being on arcs of the same radius as the roller elements. In these respects, it is pointed out that the tool motor 6 is of the reversible type, the roller elements 15

engaging the side edges 16 of the abutments in a right-hand or clock-wise rotation of the tool motor, while the side edges 16a are engaged by the roller elements in a left-hand or counter clock-wise rotation of the tool motor. The first mentioned direction of rotation is employed for screwing up a nut or bolt with a right-hand thread or removing one with a left-hand thread. The reverse direction of rotation is employed for screwing up a nut or bolt with a left-hand thread or removing one with a right-hand thread. In both cases, the power of the tool is utilized in these operations and the motor section 1 is provided with a reversing valve 11 having an adjusting handle 18 as shown in Fig. 1. When the valve 11 is set as shown in Fig. 1, the tool motor rotates in a right-hand direction. This reversing valve and its handle form no part of this present invention and need not be further described. It may be remarked, however, that the motor section 1 of the tool is provided with the necessary complement of ports and passages for rotating the motor in opposite directions. Such porting arrangements are well known in this art.

The hammer member 8 is a solid metal member of the size, strength and mass required to impart the necessary hammer blows on the abutments and is provided with a pair of diametrically disposed recesses 19, 19 to mount the roller elements 15 as shown herein. The recesses 19 open outwardly through the periphery of the hammer member whereby the roller elements 15 may be projected into the track-ways to engage the abutments 13. The recesses 19 extend axially of the hammer member 8 for the greater portion of its length and the roller elements 15 are like length to strike lengthwise against the abutments 13. The latter conform to the length of the recesses as shown by the dotted lines in Fig. 1. This provides a powerful tool comparative to its size and weight and results in tight clamping of the nuts or bolts being set and the loosening of tight ones on removing the same.

As shown in Figs. 2 and 4, the recesses 19 widen outwardly from the axis of the hammer member 8 and have circumferential and radial dimensions greater than the diameter of the roller elements therein contained. The roller elements are alike and the recesses are alike. These widening recesses 19 give the roller elements relatively free sliding and rotative movement within the hammer member 8 to engage and release the abutments as shown by the full and dotted line positions, respectively, in Fig. 2. These actions will be presently described, it being noted in passing that the intermediate surfaces 20 of the abutments 13 are on substantially the same radius as the hammer member to separate the roller tracks 14.

The hammer member 8 provides the recesses 19 with upper and lower wall sections 21, 22. These wall sections confine the roller elements against axial displacement, there being sufficient clearances provided between the ends of the roller elements and the wall sections for free sliding movement of the rollers into and out of engagement with the abutments. In these respects, the wall sections have flat inner surfaces and the roller elements have flattened ends 23 as shown in Fig. 1. The opposite end portions 24, 24 of the roller elements are tapered to prevent the extremities of the rollers striking against the abutments in case of tilting of the rollers in the recesses. Hence, the mean striking force of the

blow is preserved for the intermediate body portions of the roller elements.

The upper annular wall member 21 of the hammer member 8 fits within the like shaped upper end of the anvil member 11, the upper ends of the abutments 13 terminating short enough to receive said wall member within the anvil member as shown in Fig. 1. The lower wall member 22 of the hammer member seats within a chamber provided at the bottom wall 25 of the anvil member 11 and it is from this bottom wall that the spindle 10 depends. The hammer member 8 is provided at its lower wall 22 with a centrally located depending shaft 26 which has bearing within the hollow spindle 10. The upper wall member 21 of the hammer has a centrally located opening 27 to receive the lower annular end portion 28 of the motor shaft 1 as shown in Fig. 1. This arrangement mounts the hammer member 8 within the anvil member 11 in concentric relation and provides for relative rotation between the parts when desired.

The hollow anvil spindle 10 has a length to extend out of the housing 9 at the lower end of the tool and receives the stem or shank 29 of an adapter 30 for attaching any one of a number of nut or bolt driving sockets 31 to the tool. The bolt to be driven in Fig. 1 is marked 32.

The adapter stem 29 may be a hex and the bore of the spindle 10 has the same shape to drive the adapter. A cross-pin 33 is employed to keep the parts in assembly, but permitting a change of adapters. The latter have square outer ends to mount bolt or nut driving sockets 31. The adapter carries a spring biased detent 34 for releasably connecting the driving socket. The arrangement described gives the tool a wide range for overlapping nut and bolt sizes.

The flexible drive between the tool motor and the hammer member comprises a drive plate 35 directly connected to the motor shaft 1 through a square section 36 thereon as shown in Fig. 1. The plate 35 and the top wall 21 of the hammer are in axial alignment and have engaging hub portions 37, 38 which space the outer portions of the plates apart to accommodate the interposed lugs 39, 40 thereon. These lugs are arranged in pairs on the respective plates as shown in Fig. 3 with a spacing between the lugs to provide a lost-motion drive between them. The lugs 39, 40 provide a drive in either direction of rotation of the tool motor.

In a screwing up operation, the tool is applied with its socket over the nut or bolt to be driven and the power is turned on. The roller elements 15 are moved by centrifugal force into the track-ways 14 and engage the abutments 13 rotating the anvil with the hammer member to drive the nut or bolt. When the nut or bolt sets or tightens against the work, the anvil member 11 is held solidly against rotation and the hammer member under the drive of the motor forces the roller elements back into the recesses 19 to release the abutments. In this action, the motor accelerates and centrifugal force moves the roller elements into the path of the abutments to impart relatively strong rotational hammer blows thereon to further tighten the nut or bolt. The action repeats rapidly as the tool is retained applied to the nut or bolt and a comparative tight clamping results. In an unscrewing operation, the impact action takes place first, the roller elements striking against the abutments to loosen a tight nut or bolt.

In an impact action, when the roller elements

15 strike against the side edges of the abutments as for example at the points A in Fig. 2, the lugs 39, 40 of the drive are in solid driving engagement as will be apparent from Fig. 3 wherein the arrow a indicates the direction of rotation. The resultant action of this impact of the roller elements on the abutments forces the roller elements towards the opposed leading side walls 41 of the recesses 19 along a line indicated by the arrow B in Fig. 2. The roller elements 15 would strike with considerable force against the leading side walls 41 at the points C if the hammer member at this moment were directly connected with the driver 35 causing premature wear at the points of impact. The roller elements would also rebound from these solid blows and strike against the abutments on the surfaces 20 as at points D causing wear. With the spacing between the lugs 39, 40, the impacts at C force the hammer member ahead of the driver 35 and these impacts are absorbed in overcoming the inertia of the hammer member in throwing it ahead of the driver. Hence, the roller elements may be made to strike relatively powerful blows and respond quickly to the speed of the motor as the lugs close into driving engagement.

The machine shown and described has been designed to have the minimum number of parts for the striking mechanism, large striking surfaces for the rollers with no adjustments required. The parts are all of a heavy metal construction and are rigidly clamped together providing an effective impact tool.

The details of construction and arrangement of parts shown and described may be variously changed and modified without departing from the spirit and scope of my invention, except as pointed out in the annexed claims.

I claim as my invention:

1. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said hammer member providing side and end walls for the recesses for retaining the roller elements in operative position therein, said roller elements fitting wholly between the end walls of the recesses and having their opposite ends in sliding contact therewith, and means for rotating the hammer member.

2. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said hammer member providing side and end walls for the recesses for retaining the roller elements in operative position therein, said roller elements fitting wholly between the end walls of the recesses and having their opposite ends flattened and in sliding contact therewith, and means for rotating the hammer member.

3. An impact clutch of the character described

75

comprising, relatively rotatable hammer and anvil members, the anvil member having a wall surrounding the hammer member and provided with internal abutments and track-ways therebetween, roller elements carried by the hammer member within recesses therein and movable by centrifugal force outwardly of the recesses into the track-ways for delivering a series of rotational hammer blows on the abutments in the rotation of the hammer member relatively to the anvil, said hammer member providing the recesses with divergent side walls and end walls for retaining the roller elements in operative position therein, said recesses having circumferential and radial dimensions greater than the diameter of the roller elements whereby the latter may release and pass the abutments when moved back into the recesses, said roller elements fitting wholly between the end walls of the recesses and having their opposite ends in sliding contact therewith, and means for rotating the hammer member.

4. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said trackways being in arcuate form on a radius slightly greater than the radius of the hammer member and said abutments having blow receiving surfaces on the opposite sides thereof to receive impacts from the roller elements in either direction of rotation of the hammer member, said hammer member providing side and end walls for the recesses for retaining the roller elements in operative position therein, said roller elements fitting wholly between the end walls of the recesses and having their opposite ends in sliding contact therewith, and means for reversely rotating the hammer member.

5. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said hammer member providing side and end walls for the recesses for retaining the roller elements in operative position therein, said roller elements fitting at their ends between the end walls of the recesses with sufficient clearances for sliding contact therewith, the opposite ends of the roller elements being tapered to prevent the extremities of the roller elements striking the abutments on tilting of the roller elements in the recesses, and means for rotating the hammer member.

6. A clutch of the character described comprising, relatively rotatable members, roller elements interposed therebetween for clutching and declutching said members, said roller elements being slidably mounted at their ends in recesses in one of said members, said roller elements having their opposite ends tapered to prevent their extremities engaging the other member on tilting

of the roller elements in the recesses, and means for imparting rotation to the clutch.

7. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said hammer member providing side and end walls for the recesses for retaining the roller elements in operative position therein, a rotary driver for rotating the hammer member, a lost-motion connection between the driver and the hammer member whereby the impact of the roller elements on the leading side walls of the recesses on releasing the abutments will rotate the hammer member ahead of the driver to absorb the impacts by overcoming the inertia of the hammer member, and means for rotating the driver.

8. An impact clutch of the character described comprising, relatively rotatable hammer and anvil members, the anvil member having a wall surrounding the hammer member and provided with internal abutments and track-ways therebetween, roller elements carried by the hammer member in recesses therein and movable by centrifugal force into the track-ways for delivering a series of rotational hammer blows on the abutments in the rotation of the hammer member relatively to the anvil, said hammer member providing the recesses with side and end walls for retaining the roller elements in operative position therein, a rotary driver for rotating the hammer member, co-operating lugs on the driver and the hammer member providing a lost-motion connection therebetween whereby the impact of the roller elements on the leading side walls of the recesses on releasing the abutments will rotate the hammer member ahead of the driver to absorb the impacts by overcoming the inertia of the hammer member, and means for rotating the driver.

9. An impact tool of the character described comprising, a power operated motor, a spindle, an impact clutch interposed between the motor and the spindle and having relatively rotatable hammer and anvil members and interposed roller elements carried by the hammer member and engageable with the anvil member for clutching and declutching the same and for delivering rotational hammer blows on the anvil member in the rotation of the hammer member relatively to the anvil member, said anvil member driving the spindle and having abutments to be engaged by the roller elements, and a lost-motion connection between the motor and the hammer member comprising co-acting means for engaging following an impact of the roller elements on the abutments to directly rotate the hammer member ahead of the motor to absorb the impact by overcoming the inertia of the hammer member.

10. An impact clutch of the character described comprising, relatively rotatable hammer and anvil members and interposed roller elements for clutching and declutching said members and for delivering rotational hammer blows on the anvil member in the rotation of the hammer member relatively to the anvil member, a rotary driver for the clutch, means providing a flexible driving connection between the driver and the clutch

having circumferentially spaced co-acting means for positively picking up the hammer member following impacts of the roller elements on the anvil member to rotate the hammer member ahead of the driver to absorb the impacts in overcoming the inertia of the hammer member, and means for rotating the driver.

11. An impact clutch of the character described comprising, relatively rotatable hammer and anvil members, the anvil member having a wall surrounding the hammer member and provided with internal abutments and track-ways therebetween, said abutments providing relatively abrupt shoulders having lateral impact receiving surfaces extending inwardly from said track-ways, roller elements revolvably carried by the hammer member in radial recesses therein and movable in response to centrifugal force into the track-ways for delivering a series of rotational hammer blows on the shoulders at the lateral impact receiving surfaces thereof in the rotation of the hammer member relatively to the anvil member, and means for rotating the hammer member.

12. An impact clutch of the character described comprising, relatively rotatable hammer and anvil members, the anvil member having a wall surrounding the hammer member and provided with internal abutments and track-ways therebetween, said abutments providing relatively abrupt shoulders having lateral impact receiving surfaces extending inwardly from the track-ways, roller elements revolvably carried by the hammer member in radial recesses therein and movable in response to centrifugal force into the track-ways for delivering a series of rotational hammer blows on the shoulders at the lateral impact receiving surfaces thereof in the rotation of the hammer member relatively to the anvil member, said hammer member and means revolute therewith providing side and end walls for said recesses for retaining the roller elements in operative position therein, said roller elements fitting wholly between the end walls of the recesses and having their opposite ends opposed to said end walls, and means for rotating the hammer member.

13. An impact clutch of the character described comprising, relatively rotatable hammer and anvil members, the anvil member having a wall surrounding the hammer member and provided with internal abutments and track-ways therebetween, said abutments providing relatively abrupt shoulders having lateral impact receiving surfaces extending inwardly from said track-ways, roller elements revolvably carried by the hammer member in radial recesses therein and movable in response to centrifugal force into the track-ways for delivering a series of rotational hammer blows on the shoulders at the lateral impact receiving surfaces thereof in the rotation of the hammer member relatively to the anvil member, said hammer member and means revolute therewith providing side and end walls for said recesses for retaining the roller elements in operative position therein, said roller elements fitting wholly between the end walls of the recesses and having their opposite ends relatively close to said end walls for slidably engagement therewith, and means for rotating the hammer member.

14. An impact clutch of the character described comprising, relatively, reversibly, rotatable hammer and anvil members, the anvil member having a wall surrounding the hammer member and

provided with internal abutments and track-ways therebetween, said abutments providing relatively abrupt shoulders having lateral facing impact receiving surfaces on opposite sides thereof and extending inwardly from said track-ways, roller elements revolvably carried by the hammer member in axially extending recesses therein and movable in response to centrifugal force into the track-ways for delivering a series of rotatable hammer blows on the shoulders at the lateral impact receiving surfaces thereof in either direction of rotation of the hammer member relatively to the anvil member, and means for rotating the hammer member in either direction.

15. An impact clutch of the character described comprising, hammer and anvil members relatively rotatable about a common axis, said anvil member having relatively abrupt impact receiving surfaces, elongated roller elements rotatable with the hammer member and centrifugally urged into impacting relation with said impact receiving surfaces on rotation of the hammer member, said hammer member having driving surfaces for driving the roller elements, said driving and impact receiving surfaces being substantially co-extensive in length with the peripheral portions of the roller elements driven by the hammer member against the impact receiving surfaces in the rotation of the hammer member relatively to the anvil for imparting 30 rotational hammer blows thereto, and means for rotating the hammer member.

16. An impact clutch of the character described comprising, hammer and anvil members relatively rotatable about a common axis, said anvil 35

member having relatively abrupt impact receiving surfaces, elongated roller elements revolvably carried by the hammer member in radial recesses therein and centrifugally urged into impacting relation with the impact receiving surfaces on the rotation of the hammer member, said recesses receiving the whole of the roller elements and having wall portions forming driving surfaces for the roller elements, said driving and impact surfaces being substantially co-extensive in length with each other and with said roller elements and engageable with the peripheral portions thereof for the major portion of their length for imparting rotational hammer blows against the anvil member for rotating the same on the rotation of the hammer member relative to the anvil member, and means for rotating the hammer member.
